UNITED STATES PATENT OFFICE.

EDWARD B. HESS, OF NEW YORK, N. Y., ASSIGNEE TO ROYAL TYPEWRITER COMPANY, OF HOBOKEN, NEW JERSEY, A CORPORATION OF NEW JERSEY.

TYPE-WRITING MACHINE.

No. 916,865.

Specification of Letters Patent. Patented March 30, 1909.

Application filed July 9, 1907. Serial No. 382,820.

To all whom it may concern:

Be it known that I, EDWARD B. HESS, a citizen of the United States, residing in the borough of Brooklyn, city and State of New York, have invented certain Improvements in Type-Writing Machines, of which the following is a specification.

The improvement in typewriting machines contemplated by this invention is a new mechanism for giving to a ribbon vibrating guide different ranges of movement to effect printing from different zones of the ribbon which may be of different colors and, if desired, also to avoid interposition of the ribbon at the printing point when stencil work is being made. The style of the machine to which this part of the invention relates is therefore a visible writing machine in which, at the moment of impact of the type against the platen, the ribbon is interposed to effect an impression upon the paper and immediately thereafter it moves away from the printing point to expose to view what has been printed. There are various styles of such machines and this invention is not restricted in its application to any particular machine of that kind.

Upon perusal of this specification, it will become obvious to those skilled in the art that the invention is in no wise dependent upon the mode of operating the type bars or upon other details of construction of a writing machine and that it is equally applicable to machines printing upper and lower case in which either the platen or type bar segment is shifted.

The primary point of novelty in this part of the invention is the provision of a bar or part, arranged transversely of the machine, operated on depression of the several finger pieces in the key board and so constructed or provided with means that at will of the operator different ranges of movement are imparted to it on depression of the finger pieces to effect through appropriate actuating devices different ranges of movement of the ribbon guide or vibrator. This bar or part is preferably the universal bar of the machine. If, for instance, the ribbon vibrator be connected by suitable levers with this bar, the zone of the ribbon most nearly adjacent the printing point will be moved into position to print when a small range of movement is imparted to the bar and when a greater range of movement is imparted to it

there will, of course, be an increased amplitude of movement of the ribbon vibrator to bring a zone of the ribbon more remote from the printing point into printing position. Provision is made for timely and proper actuation of the escapement and also for an adjustment of the parts by means of which the ribbon is not projected to the printing point thereby adapting the machine to stencil work. The principles of construction by which these results may be accomplished and the mechanical details which experience has demonstrated to be practical and efficient are hereinafter set forth.

The invention is shown as applied to a front-strike, bar, key-lever, carriage shift machine, that being the general style of machine to which the invention has been first adapted by me.

In the accompanying drawing: Figure 1 is a front elevation: Fig. 2, a vertical longitudinal section: Fig. 3, a detail perspective view on an enlarged scale showing the universal bar and ribbon and escapement levers: and Fig. 4, an elevation of one end of the universal bar.

All parts of a writing machine deemed unnecessary to a clear understanding of the invention have been omitted from the drawings.

a is the rock shaft of the universal bar *b* and is connected with it by arms *c*, *c*. The rock shaft turns in suitable bearings at the sides of the machine of which *d* are the side plates and the universal bar is held up by springs *c'* applied to the arms *c c*. Springs and stops to limit movements of parts against reaction of the springs will of course be provided where needed.

In the form of invention which I had elected to illustrate different ranges of movement are imparted to the universal bar by adjustment of the bar at different elevations with respect to the parts—as key levers—which act upon it on depression of the finger pieces. By such adjustment under ready control of the operator the universal bar may be so set that all the characters will print from the upper zone of the ribbon. By another adjustment they may be all caused to print from another zone. The same result may be obtained, however, in various other ways as, for instance, in the way shown in my application No. 372,465 filed May 8, 1907 wherein the universal bar is made revoluble and has

multiple faces of different radius. In the present case, as in that application also, the universal bar is made to perform also its usual function of operating the carriage escapement. The universal bar *b* is formed at each end with a cam-like slot having three surfaces of rest of different elevations marked 1, 2, 3 and in these slots fit headed bolts *e* projecting from the arms *c*, *c*. As shown, therefore, the bar has three adjustments. When the bolts are in the parts 1 of the slots, the extent of movement of the universal bar will be such as to cause printing from the lower zone of a two zone ribbon. When they are in the parts 2, printing will be from the top zone; and when in the parts 3, the ribbon vibrator will remain at rest when stencil work may be done. This adjustment may be conveniently effected by a rod *b'* extending through the side plate *d* by manipulation of which the bar may be adjusted endwise. It is held in adjusted position by a spring *b''* engaging three notches in its upper edge.

The ribbon vibrating lever *f* rocks upon shaft *a* and has a forwardly extending end through an aperture in which passes a rod *c'* extending between the arms *c*. The other end of the lever extends upwardly and is jointed at *f'* to a link *f''* that is pinned to the downwardly extending arm of a bell crank lever *g* pivoted in a projection *g'* extending downwardly from the front rail of a shifting carriage. The other end of the bell crank lever extends forwardly and is connected at its end with a vertically movable ribbon vibrator *h*. The escape lever *i* rocks loosely about shaft *a* and extends forward under the universal bar and also upwardly. Its upper end is jointed to a link *i'* that has pivoted to its end a short bolt or screw threaded link *i''* that passes through the end of a rocking escapement lever *j* and has an adjusting nut *i'''* applied to its threaded end. The parts are so arranged and proportioned that in either the first or second position of the bar, the ribbon vibrator will first be actuated and then the escapement lever operated. In the third position, *i. e.* the lowermost position of the universal bar, its slight downward movement is merely sufficient to operate the escapement and the last motion of the connections *f*, *f'*, *g*, *h*, is such that the ribbon vibrator need not be elevated at all. However, to provide for exact elevations of the ribbon vibrator and to prevent overthrow thereof, there is provided a stop plate *k* through an aperture in which passes the forwardly extending arm of the bell crank *g* and the upper wall of which has three portions 4, 5, and 6 of different elevation corresponding with the parts 1, 2, 3, of the universal bar adjusting slot. When, as in Fig. 1, the arm of the bell crank is immediately opposite or undersurface 65 face 4, the universal bar is in its lowermost

position and the ribbon vibrator is prevented from rising. When, however, the plate *k* is shifted to the right, as viewed in Fig. 1, and the part 5 thereof is opposite or over the arm of the bell crank, the ribbon vibrator is permitted to rise sufficiently to bring the upper zone of the two-zone ribbon into printing position and by further shifting the plate to bring the part 6 thereof above the bell crank lever, the vibrator will rise to greater elevation to bring the lower zone of the ribbon into printing position. The adjustment of the ribbon vibrator stop device may be effected by hand independently of the adjustment of the universal bar but naturally it is preferred that on adjustment of the universal bar the stop devices will be automatically correspondingly adjusted. This may be conveniently accomplished in the manner shown in the drawing.

Projecting rearwardly from the right hand end of the universal bar is a horizontal pin *m* that embraces the forked end of a vertical lever *m'* pivoted at *m''* and having its upper end forked to embrace a pin *m'''* projecting from the face of a transverse sliding bar *k'* to which the stop plate *k* is attached or with which it may be integral. Other forms of stop devices may, of course, be employed. I have shown another construction of stop devices performing the described function in my prior application above mentioned.

Except as specifically stated in the claims, this invention is not limited to the details of construction shown since obviously they may be varied and the same general results obtained by other organizations which may readily be devised by skilled mechanicians.

Normal position of the parts is determined by an adjustable eccentric stop *o* against which lever arm *i* is thrown by reaction of the universal bar springs *c'*, *c''*.

I claim:

1. A ribbon vibrating guide, a transverse bar capable of different degrees of lateral movement to effect different ranges of vibration of the ribbon guide, an operating connection between the guide and bar, means for holding said bar in different normal lateral position to effect in each position uniform movement of the ribbon guide and endwise movable means for at will changing the normal lateral position of the bar so that another range of movement is imparted to it to effect a different range of movement of the ribbon guide, escapement devices, a lever for operating them and means whereby on depression of a finger piece said bar in its movement from either of said normal positions effects also operation of the escapement devices.

2. A visible writing machine, comprising a platen, a ribbon vibrator that normally holds the ribbon to one side of the line of print, finger pieces, means adapted to act

upon a universal bar on depression of the finger pieces, a universal bar provided with endwise movable means under control of the operator whereby it may have different extents of movement on depression of the finger pieces, and an operating connection between the universal bar and the ribbon vibrator.

3. A visible writing machine, comprising a platen, a ribbon vibrator that normally holds the ribbon to one side of the line of print, finger pieces, means adapted to act upon a universal bar on depression of the finger pieces, a universal bar provided with endwise movable means under control of the operator whereby it may have different extents of movement on depression of the finger pieces, an operating connection between the universal bar and the ribbon vibrator and escapement devices actuated by the universal bar whenever the said finger pieces are depressed.

4. In a visible writing machine, a platen, a ribbon vibrator, finger pieces, a universal bar, devices acting, on depression of the finger pieces, upon the universal bar, endwise movable means under control of the operator for adjusting the normal position of the surface of the universal bar upon which said devices act to thereby, at will, cause the bar to have different extents of movement when finger pieces are depressed, and an operating connection between the universal bar and the ribbon vibrator.

5. In a visible writing machine, a ribbon vibrator, a universal bar, an operating connection between the two, means for operating the universal bar on depression of the finger pieces of the machine, endwise movable means under control of the operator whereby the universal bar may be adjusted so as to have different ranges of movement

on depression of the finger pieces, and ribbon vibrator stop devices adjusted to the vibrator by the adjustment of the universal bar.

6. In a visible writing machine, a ribbon vibrator, a universal bar, an operating connection between the two, means for operating the universal bar on depression of the finger pieces of the machine, endwise movable means under control of the operator whereby the universal bar may be adjusted so as to have different ranges of movement on depression of the finger pieces, ribbon vibrator stop devices adjusted to the vibrator by the adjustment of the universal bar, escapement devices and an operative connection between them and the universal bar acting to operate said devices whenever the universal bar is operated by any of said finger pieces.

7. A ribbon vibrator, a universal bar, an operative connection between the two, key levers and means for moving the universal bar transversely endwise to adjust it to different elevations.

8. A ribbon vibrator, a universal bar, an operative connection between the two, levers arranged above the universal bar, means for adjusting the universal bar endwise to positions of different elevation, a stop device having surfaces of different elevation for limiting the throw of the vibrator and an operative connection by which said stop devices are automatically correspondingly adjusted when the universal bar is adjusted.

In testimony whereof, I have hereunto subscribed my name.

EDWARD B. HESS.
